DESIGN FOR A SWITCH AND FUSE SECURING CLIP

David Conlan, New York, N. Y., assignor to
Conlan Electric Corporation, New York, N. Y.

Application December 6, 1944, Serial No. 116,752

Term of patent 14 years

(Cl. D26—1)

To all whom it may concern:

Be it known that I, David Conlan, a citizen of the United States, residing at New York, in the county and State of New York, have invented a new, original, and ornamental Design for a Switch and Fuse Securing Clip, of which the following is a specification, reference being had to the accompanying drawing forming part thereof.

Fig. 1 is a perspective view of a switch and fuse securing clip embodying my new design; and

Figs. 2 and 3 are front and side views of the same.

I claim:

The ornamental design for a switch and fuse securing clip, substantially as shown.

DAVID CONLAN.
